UNITED STATES PATENT OFFICE.

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MEASURED-SERVICE TELEPHONE SYSTEM.

Application filed June 3, 1922, Serial No. 565,734. Renewed October 19, 1927.

The present invention relates in general to measured service telephone systems, and more particularly, to automatic measured service systems in which a type of paystation apparatus is provided at each subscriber's station requiring the deposit of a coin for each successful connection.

In one well known arrangement, the calling device at the subscriber's substation is normally inoperative to control the central office switches and it is only by first depositing a coin that the subscriber is enabled to render his sender operative to control the switches in the exchange to set up a connection. Thereafter the coin deposited is either collected or refunded depending upon whether the subscriber called responds or not. If the party called is an official of the telephone company or an operator the coin is refunded in any case.

Certain improvements have been devised in the above mentioned system whereby a calling subscriber must deposit a coin before making a call provided he desires a connection with another subscriber, while if he desires a connection with an operator no coin is required to be deposited. A particular object of the invention is to provide new circuits for a type of repeater which is used in such an improved system whereby the coin collecting and refunding operations may be controlled over the two line conductors of a calling subscriber's line in series instead of over one line conductor to ground which, so far as applicant is aware, has been the practice heretofore.

There are other objects of the invention, which together with those enumerated above, will be described hereinafter with reference to the accompanying drawings forming part of this specification.

Referring now to the drawings comprising Figs. 1-4, inclusive, there is shown by means of the usual circuit diagrams, enough of the apparatus involved in the invention to enable it to be readily explained and understood.

Referring now particularly to Fig. 1, the substation A is of the automatic type having the usual talking instrumentalities and an impulse sender S. Being a measured service substation telephone, there is also provided a well known type of coin collecting mechanism which may be of the type shown and described in the U. S. patent to

Forsberg No. 1,043,219, granted Nov. 5, 1912.

The line conductors 11 and 12 extend from the subscriber's substation to the exchange and, at the latter point, terminate in an individual trunk selecting or line switch C. This switch is of the usual rotary type in which the wipers have no normal position, always remaining in engagement with the bank contacts associated with the trunk line last used; and its function is to extend the line, when calling, to an idle trunk line terminating in a first selector switch. One of the trunk lines to which the line switch C, in common with a plurality of other line switches has access, is shown extending to the first selector E', Fig. 3. The relay equipment in Fig. 2, indicated by the reference character D is a repeater, there being one such repeater inserted in each first selector trunk. At T is shown a discriminating tone machine whose function is to give a discriminating tone to a recording operator should one be called by the subscriber, indicative of his status, that is, whether he is entitled to certain toll connections or not.

The first selectors such as E' are the first in the series of numerical switches which may comprise first selectors, second selectors, and connectors, which are used to complete connections between calling and called lines. The selector E', Fig. 3, is a switch of the well known Strowger vertical and rotary type and has access to trunk lines extending to second selectors such as E² and E³. The second selector E² is similar to the first selector E', as is the second selector E³. However, the circuits of the second selector E³ differ slightly from those of the other two switches and this will be explained shortly.

The connector H, Fig. 4, is one of the connector switches accessible to the second selector E³ and is of the well known Strowger vertical and rotary type which may be seized by means of a second selector in order to complete a connection to a called substation such as the one shown at A'.

The substation A' is one of the substations to which the connector H has access and may be similar to the one shown at A, although for convenience the measured service equipment has been omitted.

It is customary in automatic exchanges to provide a special group of second selectors

through the medium of which a calling subscriber may connect with the various groups of trunk lines extending to the different operators and employees of the telephone company, such for example, as the information operators, trouble operators, recording operators, or the wire chief. The special second selectors are generally accessible from a certain level in the regular first selectors. In Fig. 3 a trunk line is shown which terminates in a set of bank contacts in a level of the first selector E' and which extends to the second selector E². The second selector E² is one of a group of special second selectors which have access to the groups of trunk lines above referred to. One of these trunk lines is shown in the drawings and terminates in the recording operator's equipment indicated by the reference character O which comprises a group of relays, an induction coil, an answering jack J, and a call signal lamp L².

In order to explain the operation of the circuits in detail it will first be assumed that the subscriber at substation A desires to call the recording operator at whose position the jack J appears, it being possible to accomplish this connection without depositing a coin as was mentioned hereinbefore. When the receiver is removed at the substation A the line relay 26 of the individual line switch C is energized over the line conductors 11 and 12 in series. Relay 26, upon energizing, at its armature 34 completes a circuit for the switching relay 25 in series with the motor magnet 27. Another result of the energization of relay 26 is that at armature 33 the test wiper 39 is connected midway between the switching relay 25 and the said motor magnet. The operation of the line switch C depends upon whether the trunk line with which its wipers 38-40, inclusive, are in engagement is busy or not. Assuming this trunk line to be busy, there will be a ground potential upon the test contact engaged by the test wiper 39, the switching relay 25 is short circuited and the motor magnet 27, being supplied with direct ground via the said test wiper, will operate as a buzzer to advance the wipers of the switch step by step in search of a bank contact set which is associated with an idle trunk line. However, it will be assumed in the present case that when the receiver is removed at substation A the switch wipers 38-40, inclusive, are in engagement with the bank contacts associated with an idle trunk line, and it will be assumed further, that this trunk line is the one terminating in bank contacts 45-47, inclusive. Under these conditions, immediately following the energization of the line relay 26 the switching relay 25 will energize. Upon energizing, relay 25 disconnects the line conductors 11 and 12 of the calling substation from the winding of the line relay

26 and from ground, respectively, and extends them by way of armatures 30 and 32, wipers 38 and 40, trunk conductors 48 and 50, armatures 120 and 123, armatures 139 and 142, to the upper and lower windings of the line relay 110 of the repeater D.

The line relay 110 of the repeater D is energized over the two sides of the calling line in series and at its armature 147 completes the circuit of the slow acting relay 111. The latter relay, upon energizing, at its armature 149 places ground upon the release trunk conductor 49 by way of the retardation coil 114 thereby establishing a holding circuit for the line switch C, which extends by way of bank contact 46, test wiper 39, armature 31 and its front contact, through the winding of the switching relay 25, and thence through the winding of the motor magnet 27 to battery. It will be understood that this holding circuit is established before the slow acting relay 26 has had time to deenergize and serves to maintain the switching relay energized throughout the connection. A branch of this holding circuit also extends by way of private normal conductor 28 to the multiplied test contacts in the banks of connector switches which have access to the line of the substation A whereby the said line is protected from intrusion in the usual manner.

It will be remembered that ground is supplied to the release trunk conductor 49 through the retardation coil 114. This coil is of very low resistance say of about 2 ohms so that the multiples of the test contact 46 accessible to the other line switches are made busy. Other results of the energization of the slow acting relay 111 are that at armature 151 a circuit is prepared for the slow acting relay 107, at armature 152 a circuit is completed for the slow acting relay 105, and also for the polarizing winding of the electro-polarized relay 106, and at armature 150 a circuit is completed for the relay 112 in series with the resistance 199. Relay 105, upon energizing, at armature 135 establishes a locking circuit for itself, at armature 136 places an additional ground upon the release trunk conductor 49, at armature 137 prepares a point in a circuit for relay 107, and at armature 138 opens a point in the circuit of the upper winding of relay 108. The electro-polarized relay 106 does not energize at this time, as the current flow in its polarized winding does not attract the armatures, though after once being operated the current flow in the polarizing winding is sufficient to maintain its armatures attracted. The relay 112 is energized in series with the resistance 199 and operates at armature 154 to open a point in a certain shunt circuit which will be later described.

It will be noted that the circuit of the line relay 110 includes the relay 109 in series

with it. Relay 109 energizes in series with the line relay 110 and at armature 146 opens a point in the circuit of the relay 113. Another result of the energization of line 5 relay 110 is that a bridge is closed across conductors 200 and 202 which may be traced as follows: trunk conductor 200, armature 143 and its back contact, normally closed springs controlled by armature 139, through 10 the lower winding of electro-polarized relay 106, through the lower winding of relay 108, front contact and armature 148, normally closed springs controlled by armature 142, to conductor 202. Upon the closure of 15 the above circuit the line relay 225 of the first selector E' is energized. Upon operating, relay 225 completes the circuit of the slow acting release relay 226 which immediately operates to prepare the operating 20 circuits of the selector E' at armature 238, and at armature 237 places ground upon the release trunk conductor 201 through the resistance 240. This ground extends back over the release trunk conductor 201, through the 25 resistance 199 in the repeater D to battery. The relay 112 is not short circuited at this time as the resistance 240 is high enough to prevent the relay winding from being shunted.

30 Before proceeding further with the explanation attention is called to a shunt circuit around armature 148 and its front contact which, it may be mentioned, are the impulse springs of the repeater D that control 35 the operation of the selector E' and succeeding switches. This shunt circuit extends as follows: from armature 148, armature 153 and its front contact, back contact and armature 156, back contact and armature 154, 40 to front contact of armature 148. Contacts 153 and 156 on relays 111 and 113 are closed but, as the relay 112 is energized, armature 154 will be in an attracted position and the shunt circuit will be opened at this point, 45 it being clear from this explanation that the shunt circuit will not interfere with the operation of the impulse springs represented by armature 148 and its working contact in repeating impulses.

50 Referring now to the substation A it will be noted that the impulse springs on the calling device S are shunted when no coin is deposited in the paystation apparatus by the resistance 5. While this resistance is high 55 enough to allow the line relay 110 to deenergize when the calling device is operated, it allows sufficient current to pass over the line to maintain the relay 109 energized as long as it is in the circuit whether the calling 60 device impulse springs are operated or not.

The calling subscriber at substation A may now operate his calling device in accordance with the two digits which it is necessary to call in order to obtain connection with the 65 recording operator. By the operation of

the calling device S a series of interruptions is produced in the circuit of the line relay 110 of the repeater D. Line relay 110 de-energizes a plurality of times in response to such interruptions, each time opening the 70 previously traced circuit of the line relay 225 of the first selector E'. At the first de-energization of line relay 110 an impulse of current is sent to the slow acting relay 107 which is energized and maintained energized throughout the impulse series. Relay 107, upon energizing, at armature 143 places a direct bridge across the trunk conductors 200 and 202 which does not include the resistance 197, the lower winding of the electro-polarized relay 106, nor the lower winding 75 of relay 108. This circuit change is brought about in order to reduce the resistance and impedance of the switch control circuits to a minimum during the 80 transmission of impulses. The operation of the armature 144 on relay 107 is without function at the present time.

Proceeding now to the operation of the first selector E', at each deenergization of 90 the line relay 225 an impulse of current is sent to the vertical magnet 232 in series with the slow acting relay 227. Magnet 232 operates to raise the switch wipers 255-257, inclusive, step by step until they are placed 95 opposite the level of bank contacts in which are terminated trunk lines leading to the special group of second selectors which have access to trunk lines leading to operators' 100 positions. The slow acting relay 227 is energized in series with the vertical magnet and maintains its armature attracted throughout the vertical movement of the switch. Upon the first vertical step of the 105 switch, when the off normal springs are shifted, a circuit is completed extending from ground on release trunk conductor 244, armature 245 and its front contact, off normal spring 241 and its working contact, and through the winding of the stepping relay 228 to battery. Relay 228, upon energizing, 110 establishes a locking circuit for itself at armature 247, and at armature 248 prepares the circuit of the rotary magnet 231. At the

115 termination of the vertical movement of the switch, the slow acting relay 227 is deenergized and the circuit of the rotary magnet 231 is completed. Magnet 231, upon operating, rotates the switch wipers into engagement with the first set of bank contacts in 120 the selected level and at armature 254 opens the locking circuit of the stepping relay 228, which deenergizes, opening the circuit of the rotary magnet 231, which deenergizes also. The further operation of the selector E' depends upon whether or not the trunk line with which the wipers 255-257, inclusive, are now associated is busy. Assuming this to be busy, there will be a ground potential 125 present upon the test contact engaged by the 130

test wiper 256 and a circuit will be completed extending from the said grounded test contact by way of the test wiper 256, armature 251 and its back contact, armature 254 and its back contact, off normal spring 241 and its working contact, and through the winding of the stepping relay 228 to battery. Upon energizing, relay 228 establishes a locking circuit for itself and completes the 10 circuit of the rotary magnet 231. This alternate operation of relay 228 and the rotary magnet 231 will continue until the switch wipers 255-257, inclusive, are rotated into engagement with the bank contacts associated with an idle trunk line, which, we will assume, are the bank contacts 260-262, inclusive. As this trunk line is idle, there will be no ground potential present upon the test contact 261 engaged by the test wiper 256 and no circuit will be completed for the stepping relay 228. The switching relay 229 will now be energized in series with the stepping relay 228 as it is no longer short circuited. It may be stated at this point 25 that the switching relay 229 is of such high resistance that the stepping relay 228 is not energized in series with it. Relay 229, upon operating, disconnects the incoming trunk conductors 200 and 202, from the windings 30 of line relay 225 and extends them by way of armatures 250 and 253, wipers 255 and 257, bank contacts 260 and 262, trunk conductors 267' and 269, armatures 305 and 308, to the upper and lower windings of the line 35 relay 280 of the second selector E².

The line relay 280 is immediately energized and operates to complete the circuit of the slow acting release relay 281. The latter relay, upon energizing, prepares the 40 operating circuits of the selector E² at armature 292 and at armature 291 places ground on release trunk conductor 288 through the resistance 295 thereby establishing a holding circuit for the switching relay 229 of the 45 first selector E'. This ground also extends by way of the release trunk conductor 201 through the resistance 199 in the repeater D to battery, but as the resistance 295 is included in this circuit the relay 412 50 is still maintained energized and the shunt circuit around the impulse springs 148 is held open at armature 154.

The calling subscriber may now operate 55 his calling device in accordance with the second and final digit in the number of the desired operator thereby producing a second series of interruptions in the circuit of the line relay 110 of the repeater D which are repeated by means of the armature 148 to the line relay 280 of the second selector E². The selector E² is exactly like the selector E' and its operation will not be described in detail. It will suffice to say that the switch shaft is raised step by step until the wipers 60 65 310-312, inclusive, stand opposite the level

of bank contacts in which are terminated trunk lines extending to the recording operator's position, after which the wipers are automatically rotated in search of an idle trunk line. Assuming that the trunk line 70 shown in the drawings is the first idle trunk line, the switch wipers will finally be brought to rest in engagement with bank contacts 313-315, inclusive, whereupon the switching relay 284 will be energized. As a result 75 of the energization of relay 284, the trunk conductors 267' and 269 are disconnected from the windings of the line relay 280 and are extended by way of wipers 310 and 312, bank contacts 313 and 315, to the upper and lower windings of the double wound relay 320. Relay 320 is therefore energized and completes a circuit for the slow acting relay 321, which, upon energizing, in turn closes the circuit for the lamp signal L⁶ and also 80 completes the usual holding circuit for the selectors E' and E² which may be traced as follows: Ground by way of front contact and armature 328, through the primary winding 85 of the induction coil I', through the resistance 316, bank contact 314, test wiper 311, armature 306 and its front contact, where it joins the holding circuit previously described. The switching relays 284 and 229 are maintained energized and the switches E' and E² are accordingly held in their 90 operated positions.

The desired connection has now been established. The recording operator is provided with suitable cord circuits and other 100 apparatus and when she perceives the lighted condition of the lamp L⁶ she will answer the call by inserting the answering plug of one of her cord circuits into the jack J and operate her listening key. In order to determine the class of service that the calling 105 subscriber is entitled to, after operating the listening key in the cord circuit, the recording operator will throw the key K. By this operation the secondary of the induction coil 110 I' is connected in bridge of the trunk conductors and the discriminating tone on the release trunk may be heard by the recording operator over a circuit which includes the secondary of the induction coil I'. The primary of the induction coil I' is energized over a circuit which extends as follows: from the discriminating tone machine T, terminals 43 and 42, front contact and armature 31, wiper 39, bank contact 46, release trunk conductor 49, through the condenser 51, release trunk conductor 201, front contact and armature 251, test wiper 256, test contact 261, conductor 268, front contact and armature 306, test wiper 311, test contact 314, resistance 316, and through the primary winding of the induction coil I' to ground by way of armature 328 and its front contact. It will be noted that in the above circuit there are two other paths for the current 115 120 125 130 135 140 145 150 155 160 165 170 175 180 185 190 195 200 205 210 215 220 225 230 235 240 245 250 255 from the tone machine T to take, one of these paths may be traced from release trunk conductor 49 through the winding of retardation coil 114, to ground through armature 5 136 and its front contact; the other path may be traced from release trunk conductor 201 through the winding of the relay 112 to ground, by way of armature 150 and its front contact. However, as these circuits include 10 the winding of retardation coil 114, and the winding of the relay 112, both of which are of high impedance, the greater part of the current from the tone machine flows over the previously traced circuit. The class of 15 service to which the calling subscriber is entitled is determined by the particular tone which is connected to the private normal conductor of his line and which is induced in the secondary of the induction coil I' and is 20 audible to the recording operator. As soon as the recording operator determines the class of service that the calling subscriber is entitled to she will restore the key K to normal so as to communicate with the calling 25 subscriber. The recording operator may now converse with the calling subscriber in order to ascertain his desires. The talking circuit may now be traced over the heavy talking conductors and it will be noted that 30 there is a bridge across the talking circuit in the repeater which includes a winding of the electro-polarized relay 106 and the lower winding of the relay 108. The lower winding of the relay 108 operates as a retardation coil so that the transmission efficiency of the talking circuit is not materially affected by the above mentioned bridge. From this point on, the operation may take 35 any desired course, depending upon the wants of the subscriber, and will not be described. Disconnection is effected in the usual manner by the hanging up of the receiver at substation A. This operation opens the circuit of the relay 110. Relay 110, 40 upon deenergizing, sends an impulse to slow acting relay 107 and at the same time opens the circuit of the slow acting relay 111, with the result that this relay deenergizes an instant later. Relay 107, upon energizing, at 45 its armature 144 completes a circuit for relay 100. Relay 100, upon operating, at its armature 122 completes a locking circuit for relay 107, at its armature 121 breaks the locking circuit of relay 105, and at armatures 120 and 123 opens the bridge across the 50 trunk conductors 200 and 202, with the result that the relay 320 at the recording operator's position is deenergized followed by the deenergization of the slow acting relay 321. The switching relays in the selector switches E' and E² are, therefore, also deenergized and these switches are restored to their normal position in the usual and well known manner. Relay 100 at its armatures 55 120 and 123 and their front contacts also

connects ground and high potential battery B to conductors 48 and 50, respectively, but without effect as the paystation magnet 1 is not at this time connected to the line. Relay 105, upon deenergizing, at its armature 136 removes ground from the holding circuit of line switch C, permitting it to also restore in the usual manner, and at its armature 137 breaks the holding circuit of relay 107. This latter relay, upon deenergizing, at its armature 144 breaks the holding circuit of relay 100, permitting it also to restore. 70 The operation of the system when the subscriber at substation A desires connection with another subscriber will now be described. It will first be assumed that the subscriber at substation A attempts to make connection with the desired party's line without first depositing a coin at his paystation apparatus. When the receiver is removed at the substation A the operations by which the line of the calling subscriber is extended through the medium of the line switch C and the repeater D to a first selector E' are identical with the operations described in the previous case and will not be repeated. The operation of the selector E' wherein the connection is extended to a second selector likewise already have been described and in this case there is nothing new in the operation except that the wipers 255-257, inclusive, are raised opposite a bank level in which are terminated trunk lines extending to second selectors of the regular trunking system. The second selector E² is a switch of this class and it will be assumed that the trunk line extending thereto is the first trunk line found to be idle and that the selector E' establishes connection with the bank contacts 265-267, inclusive. The trunk conductors 200 and 202 will now be extended by the operation of the switching relay 229 by way of wipers 255 and 257, bank contacts 265 and 267, to the upper and lower windings of the line relay 270 of the second selector E². Upon energizing, relay 270 closes the circuit of the slow acting release relay 271. Upon attracting its armature 275 relay 271 closes a holding circuit which extends as follows: 80 ground by way of armature 275 and its front contact, test contact 266, test wiper 256, to armature 251 and its front contact, where the circuit divides, one path extending through the winding of the switching relay 229 and the interrupter relay 228 in series, to battery, and the other path extending by way of release trunk conductor 201 to junction point 195, where it joins the branch extending from ground and front contact of armature 150 in the repeater D. It will be observed that the above traced circuit contains no resistance such as resistances 240 and 295 and, as a result, relay 112 in repeater D is practically short circuited. 85 90 95 100 105 110 115 120 125 130

6
cuated. This relay therefore retracts its armature 154 and closes the previously described shunt circuit around armature 148 of the line relay 110 and its front contact, thereby rendering the armature 148 ineffective to open the bridge across the trunk conductors 200 and 202 when the relay 110 is deenergized. When the calling subscriber operates his dial in accordance with the next digit and produces another series of interruptions in the line circuit the resulting deenergizations of relay 110 will be of no effect and it will be apparent that the selector E² cannot be operated.

15 The difference in the two classes of second selectors will now be apparent. All the selectors which are required to be used in extending a connection to an operator's position or the line of an official of the telephone company are provided with resistance in their release trunks similar to the resistances 240 and 295, while those switches which are used only in connections to local subscribers have the resistance omitted. It follows then, 25 that whenever it is attempted to use a switch of the latter class, under the circumstances just described, where no coin is deposited, the relay corresponding to the relay 112 of the repeater in use will be short-circuited and 30 will deenergize to disable the operating circuit extending to the switch thus preventing further extension of the connection.

The operation of the system in the case where the subscriber at substation A deposits 35 a coin before calling the desired subscriber will now be described and in this connection the process of collecting the coin at the termination of the conversation will be briefly described. The first operation on the part 40 of the subscriber at substation A is to deposit a coin of suitable denomination in the coin collecting mechanism provided for that purpose. This mechanism is well understood and its operation need not be explained in 45 detail. When the coin is deposited it descends past the trigger mechanism which is released by the coin with the result that the polarized magnet 1 of the coin collecting mechanism is connected in series with the 50 two line conductors and the high resistance winding of relay 2 and the resistance 6, and the resistance 5 is removed from in shunt of the impulse springs of the calling device S. A coin may be deposited either before 55 or after the receiver is removed. In either case the latter action brings about the operation of the rotary line switch C whereby the line is extended to an idle first selector switch. Assuming that the selector E², Fig. 60 3, is the switch to which connection is extended, the operations are the same as have already been described in the preceding connection and will not be repeated. It may be stated at this time, however, that the 65 resistance of operating magnet 1, the left

hand winding of relay 2, and the resistance 6, is so high that it does not materially interfere with the transmission of operating impulses or with the talking circuit and it is also so high that when the first interruption 70 occurs in the line circuit the relay 109 in the repeater D deenergizes in the same manner as the line relay 110.

The calling subscriber may now operate his calling device in accordance with the 75 digits of the number assigned to the substation A', it being assumed that this line is the one desired by the calling subscriber. The selector E² will respond to the first digit in the same manner as has already 80 been described. In the repeater D the first deenergization of the relay 109 in response to the operation of the calling device, causes a circuit to be completed for the relay 113. Relay 113, upon energizing, at armature 155 85 opens the circuit of the relay 112, and at the front contact of this armature establishes a locking circuit for itself, and at armature 156 opens the shunt circuit around the impulsing spring 148 and its front contact. This latter 90 operation is an essential feature to be considered at this time for obviously it permits any of the switches in the exchange to be operated no matter whether they are provided with resistance in the release trunk such as the resistance 240 or not. Relays 109 and 113 therefore constitute means responsive to the deposit of the coin for rendering the repeater D operative to repeat impulses 95 regardless of the type of switches which it is attempted to operate.

In response to the second digit dialled by the calling subscriber a second selector E² will also be operated in the usual manner to the desired level in which are terminated 100 trunk lines leading to connector switches, such as the connector H, Fig. 4, which has access to the line of the substation A'. The selector E² will then rotate in a well understood manner to select an idle trunk line 105 which leads to an idle one of these connector switches and, which, it will be assumed, is the trunk line comprising conductors 380-382, inclusive. As this trunk line is idle, there will be no ground potential present upon the test contact 354 and the switching relay 274 will be energized in series with the stepping relay 273. Immediately upon the energization of relay 274, the trunk conductors 201 and 202 will be extended by way of wipers 110 350 and 352, bank contacts 353 and 355, conductors 380 and 382, normally closed springs controlled by armatures 416 and 417, to the upper and lower windings of the line relay 401 of the connector H.

The relay 401 is therefore energized over a circuit including the bridge in the repeater D and operates to complete the circuit of the slow acting relay 402. The latter relay energizes to prepare the impulsing circuits 115 120 125 130

of the connector H at armature 421, and at armature 420 places ground on release trunk conductor 381, thereby establishing a holding circuit for the selector switches E³ and E'.

- 5 The calling subscriber at substation A may now operate his calling device for the next digit of the desired number. By this operation, a series of interruptions is produced in the circuit of the relays 109 and 110 in the 10 repeater D. The operation of relay 109 is without function at the present time. By the operation of armature 148 on line relay 110 the interruptions produced by the calling device are repeated to the line relay 401 15 of the connector H which deenergizes a plurality of times in response thereto. At the first deenergization, a circuit is completed extending from ground by way of armature 418 and its back contact, armature 20 421 and its front contact, off normal springs 422 and 423, through the winding of the slow acting relay 403, and thence through the winding of the vertical magnet 409 to battery. The circuit above traced 25 is the one over which the first vertical magnet impulse is transmitted. Upon the first vertical step of the switch shaft, the off normal springs are shifted and the remaining impulses to the magnet traverse a new 30 circuit which is the same as the one above traced except that it includes the off normal springs 422 and 423 and armature 424 and its front contact on slow acting relay 403 which is now energized. The vertical magnet 35 409 operates to raise the switch shaft carrying the wipers 450-452, inclusive, step by step until the said wipers are brought opposite the level of bank contacts corresponding to the number of interruptions in 40 the digit dialled. The slow acting relay 403 is energized in series with the vertical magnet and maintains its armature attracted throughout the vertical movement of the switch, and at the termination thereof deenergizes, thereby transferring the impulsing 45 circuit to the rotary magnet 410.
- The subscriber at substation A may now dial the next and final digit of the desired number. As before, a series of interruptions is produced in the circuit of the line relay 110 of the repeater D and these are repeated to the line relay 401 of the connector H by means of armature 148 and its front contact. At each retraction of armature 418 on line relay 401 an impulse of current is sent over the following circuit: ground, armature 418 and its back contact, armature 421 and its front contact, off normal springs 422 and 423, armature 424 and 50 its back contact, back contact and armature 431, armature 441 and its back contact, and thence through the winding of the rotary magnet 410 to battery. The rotary magnet 410 operates to rotate the switch shaft 55 carrying the switch wipers into engagement

with the set of bank contacts associated with the line of the substation A, which, we will assume, are the bank contacts 454-456, inclusive. The slow acting relay 406 is energized in multiple with the rotary magnet, and at its armature 433 connects the test wiper 451 to the lower winding of the test relay 405, and at armature 434 short circuits the armature 431 and its back contact on the test relay 405. The latter operation 70 serves to preserve the continuity of the rotary magnet circuit while the switch wipers are being rotated over bank contact sets associated with busy telephone lines.

Assuming that the desired line is busy at 80 the present time, there will be a ground potential present upon the test contact 455 engaged by the test wiper 451 and the test relay 405 will be energized. Upon operating relay 405, at armature 430 establishes 85 a point in its locking circuit which is completed upon the deenergization of slow acting relay 406, at armature 429 short circuits the upper winding of relay 407, at armature 428 opens the circuit for its upper winding, 90 at armature 431 opens a point in the circuit of the rotary magnet, and at armature 432 connects a lead from the busy machine to the lower talking conductor. This tone is 95 audible to the calling subscriber who is thus notified that the desired line is busy and he will replace his receiver upon the switchhook thereby initiating the release of the operated switches in a manner which will 100 be described later.

It will now be assumed that the line of the substation A' is idle when the wipers 450-452, inclusive, are brought into connection with the bank contacts 454-456, inclusive. Under these conditions, there will be no 105 ground connected to test contact 455 and no circuit is completed for the lower winding of the test relay 405. Then, upon the deenergization of the slow acting relay 406, a circuit is completed extending from ground on release trunk conductor 381 by way of armature 430 and its back contact, normally closed springs controlled by armature 437, through the upper winding of the switching relay 407, back contact and armature 433, test wiper 451, test contact 455, 110 through the winding of the switching relay 470, and thence through the winding of the rotary magnet 474 to battery. The above circuit is ineffective at the present time for the reason that prior to the deenergization of the slow acting relay 406 a circuit for the upper high resistance winding of relay 405 is completed extending from ground by way 115 of back contact and armature 472 in the line switch C', bank contact 456, wiper 452, through the upper high resistance winding of relay 405, armature 428 and its back contact, front contact and armature 414, back contact and armature 435, wiper 450, bank 120 125 130

winding of relay 103, front contact and armature 130, front contact and armature 120, trunk conductor 48, bank contact 45, wiper 38, front contact and armature 30, line conductor 11, working contact of coin controlled spring 8 and the said spring, through the winding of the polarized magnet 1, through the left hand high resistance winding of relay 2, 5 through resistance 6, the ringer magnets, line conductor 12, armature 32 and its front contact, wiper 40, bank contact 47, conductor 50, armature 123 and its front contact, and thence to ground by way of armature 131 10 and its front contact. The relay 103 is energized over this circuit and, at armature 128 closes a circuit for the relay 101. Relay 101, upon operating, at armature 127 opens the circuit of the slow acting relay 107, at 15 armature 124 grounds the release trunk conductor 49, and at this same armature also connects the resistance 196 and spark condenser 195' in multiple to ground in the coin collecting circuit to reduce the sparking as is 20 the usual practice, and at armature 125 prepares an interrupted circuit for the upper winding of relay 108. Upon the deenergization of relay 105 which occurs shortly after the energization of relay 100 one ground 25 connection is removed from release trunk conductor 49 at armature 136, and at armature 138 the interrupted circuit for the upper winding of relay 108 is completed. The high voltage current flowing over the previously traced coin collecting circuit from 30 the battery B will immediately cause the relay 2 at the substation A to operate thereby bridging its low resistance right hand winding across the circuit shunting its high resistance winding and the high resistance 35 6. Ordinarily the polarized magnet 1 will respond immediately after the operation of relay 2 and will operate to collect the deposited coin and restore the entire coin collecting mechanism to normal at the same time disconnecting its windings from the line conductors 11 and 12. However, it sometimes happens that the armature of the polarized magnet will stick and the relay 45 50 108 is provided to insure the collection of the coin in such case. The interrupter I causes relay 108 to rapidly vibrate its armatures thus intermittently short circuiting the high resistance winding of the relay 103 in the coin collecting circuit with the object of intermittently energizing the polarized magnet, this operation being ordinarily effective to free the armature in case it should stick. Even with the high resistance lower winding 55 60 65 of relay 103 in its circuit the relay 2 at the substation remains operated until the coin is collected. When the coin is collected the polarized magnet 1 disconnects itself from bridge of the line conductors 11 and 12 thereby opening the circuit of the relay 103 which deenergizes to open the circuit of relay 101. Relay 101, upon deenergizing, at armature 124 removes ground from the release trunk conductor 49 and also opens the circuit for the winding of relay 104. Relay 104, upon deenergizing, opens the circuit of relay 100 at armature 134, and at armatures 130 and 131 restores certain points in the coin collecting circuit to normal. The deenergization of relay 100 restores the contacts 70 75 of repeater D to normal. The removal of ground from the release trunk conductor 49 opens the holding circuit of relay 25 in the line switch C. Upon deenergizing, relay 25 restores the circuit of the line switch to 80 normal. In this manner all the apparatus is restored to normal and is ready for another call.

Returning now to the operation of the connector H, it will be assumed that the calling subscriber at substation A replaces his receiver upon the switch-hook before the called subscriber at substation A' does. By the replacement of the receiver at the calling substation, the line relay 401 is deenergized 85 to open the circuit of slow acting relay 402. After deenergization of relay 401 and before the deenergization of relay 402, an impulse of current is sent to the slow acting relay 406. Relay 406 operates at its armature 433 to remove ground from the release trunk conductor 381 after the slow acting relay 402 is deenergized, in order to enable the previously operated switches to be released, 90 after which the connector is protected from seizure upon the deenergization of this relay by ground being connected to the release trunk over the following circuit: ground, armature 438 and its front contact, armature 433 and its back contact, armature 437 and its front contact, back contact and armature 430, to release trunk conductor 381. The relays 404 and 407 do not deenergize upon the deenergization of slow acting 95 100 105 relay 402 for the reason that their locking circuits are still energized by ground through armature 415 and its front contact on the back bridge relay 400. As the release magnet circuit is opened at armature 442 on the switching relay 407 the connector switch 110 115 is not released.

The momentary disconnection of ground from the release trunk conductor 381 causes the selectors E' and E² to be released in the same manner as before described. The disconnection of ground from the release trunk conductor 381 also opens the locking circuit of the upper winding of relay 106 120 thereby causing this relay to be deenergized. The deenergization of relay 106 brings about the collection of the coin at the calling substation and the release of the repeater D and the line switch C in the same manner as has been described.

When the called subscriber at substation 125 130 135

A' finally replaces his receiver the back bridge relay 400 deenergizes to open the locking circuit of the relays 404 and 407. The deenergization of relay 407 closes the circuit of release magnet 408 at armature 442, and at armatures 437 and 438 removes ground from the release trunk conductor 381 thereby rendering the connector H accessible through selector switches such as 10 E³. As relay 404 is slow acting it does not restore to normal until after the deenergization of relay 407. The release magnet 408 operates to release the connector H to its normal position. Thus, the connector H 15 is caused to restore to normal by the last party to replace his receiver upon the switch-hook.

In the operation of the connector H when connection was first made with the 20 line of the substation A', it will be remembered that the relay 407 was prevented from energizing to connect the ringing current until the switching relay 470 in the line switch C' energized to clear the called line 25 of attachments. This provision is made so as to guard against the possibility of the ring cut off relay energizing to disconnect the ringing current, or the line relay 471 of the line switch C' energizing to extend the line 30 of the substation A' to an idle selector, which might occur if the switching relay 407 in the connector H energized before the switching relay 470 of the line switch C. Attention is also directed to the fact that the 35 circuit of the release magnet 408 of the connector H is not closed until the wipers of the switch are disconnected by the deenergization of relay 407. Thus, the connector H in releasing, cannot interfere with the 40 operation of any of the lines to which it has access.

In case the called subscriber did not answer it will be necessary to refund the deposited coin at the paystation apparatus 45 rather than collect it when the calling subscriber replaces his receiver, and this refunding operation will now be briefly explained. Since the called subscriber did not answer neither the polarized relay 106 nor 50 the relay 104 will be energized. Now when the calling subscriber hangs up his receiver the line relay 110 of the repeater D deenergizes and sends an impulse of current to the slow acting relay 107 at the same time 55 opening the circuit of the slow acting relay 111. The latter relay, upon deenergizing, completes a circuit extending from ground by way of armature 152 and its back contact, front contact and armature 144, and 60 through the winding of the relay 100 to battery. Upon energizing, relay 100 operates as before described except that in the present case since relay 104 is deenergized the lead from the battery B is connected to 65 the lower trunk conductor 50. The current

flow from the battery B now operates the relay 103, the polarized magnet 1 at the calling substation, and the relay 2. The polarized magnet 1 is actuated to refund the deposited coin rather than collect it, as the current from the battery B is now flowing through in the opposite direction to the current flow in the former case. Another result of the energization of relay 100 is that another circuit is completed for slow acting relay 107. Relay 105, upon deenergizing, removes ground from the release trunk conductor 49 at armature 136, and at armature 137 opens the circuit of slow acting relay 107. Upon deenergizing, relay 100 80 operates to restore the circuits of the repeater D to normal. The removal of ground from the release trunk conductor 49 brings about the release of the line switch C in the usual manner. 85

The deenergization of the line relay 110 of the repeater D, of course, also brings about the release of the connector H and the first selector E' and the second selector E³ in a manner similar to that already described. 90

The features of the invention having been described and ascertained what is considered to be new and desired to have protected by Letters Patent will be pointed out in the appended claims. 95

What I claim is:

1. In a telephone system, a substation equipped with a coin box, two talking conductors extending from said substation to a central station, means at the central station for extending said conductors into connection with a called line, means for supplying talking current to said substation, a magnet in said coin box inoperative responsive to said talking current, a high voltage battery, and means for connecting said high voltage battery to one of said talking conductors to actuate said magnet to collect coins and for connecting said high voltage battery to the other of said talking conductors to refund coins deposited to pay for the extended connection. 100

2. In a telephone system, a substation provided with a coin box, two talking conductors connecting said substation with a central office, automatic switches in the central office, a calling device at said station having impulse springs bridged across said talking conductors, a magnet in shunt of said impulse springs, means for operating said calling device to control the operation of a series of said switches to extend a connection to a called line, a high voltage battery, means for applying said battery to one of said talking conductors to actuate said magnet to collect coins deposited in said coin box, and locking means for maintaining said high voltage battery connected to said line until the coins are collected. 115

3. In a telephone system, subscribers' line 120

extending to a central exchange, a station on each line, measured service equipment at the station on each line, automatic selector switches of two classes, means for operating switches of one class whether a coin is deposited in said measured service equipment or not, and means controlled exclusively over a metallic circuit for causing switches of the other class to be operative only if a coin has been deposited in said measured service equipment.

4. In a telephone system, subscribers' lines extending to a central exchange, a station on each line, measured service equipment at the station on each line, automatic selector switches of two classes, means for operating switches of one class whether a coin is deposited in said measured service equipment or not, and means controlled exclusively over a metallic circuit normally preventing the operation of switches of the other class.

5. In a telephone system, a line extending to a central exchange and having call charging equipment associated therewith, serially related automatic switches at the exchange, a repeater interposed between said line and switches, a control circuit extending from said repeater to one of said switches and including interrupter contacts for controlling the same to operate said switch, a shunt path around said contacts, and a relay in said repeater energized solely over a metallic circuit including said line to render said shunt circuit effective to shunt said contacts, another relay in said repeater for rendering said first relay ineffective, and means including said call charging equipment for rendering said last relay effective.

6. In a telephone system, a line extending to a central exchange, coin collecting mechanism at the station on said line, serially related automatic switches at the exchange, a repeater interposed between said line and switches, a control circuit extending from said repeater to one of said switches and including interrupter contacts for controlling the same to operate said switch, a shunt path around said contacts, a relay in said repeater energized solely over a metallic circuit including said line to render said shunt circuit effective to shunt said contacts, and means controlled over a complete metallic circuit including said line by the depositing of a coin in said mechanism for deenergizing said relay to render said shunt circuit ineffective.

7. In a telephone system, a line extending to a central exchange, coin collecting mechanism at the station on said line, automatic selector switches at the exchange, means for preventing said switches from being operated over said line, and means controlled over a metallic circuit completed by the deposit of a coin in said mechanism for rendering said preventing means ineffective.

8. In a telephone system, a line extending to a central exchange, coin collecting mechanism at the station on said line, serially related automatic switches at the exchange, a repeater interposed between said line and switches, a control circuit extending from said repeater to one of said switches and including interrupter contacts for controlling the same to operate said switch, a shunt path around said contacts, a relay in said repeater adapted to open said shunt circuit, and means controlled over a complete metallic circuit including said line by the depositing of a coin in said mechanism for energizing said relay.

9. In a telephone system, a line extending to a central station, coin collecting mechanism at the station on said line, serially related automatic switches at the central station of two classes, a calling device at the station on said line having impulse springs across the conductors of said line, a resistance in shunt of said springs, means for preventing the operation of switches of one class with said shunt across said springs, and means controlled by the depositing of a coin in said mechanism to remove said shunt to enable switches of either class to be operated.

10. In a telephone system, a line extending to a central exchange, serially related automatic switches at the exchange, a repeater interposed between said line and switches, a control circuit extending from said repeater to one of said switches and including interrupter contacts for controlling the same to operate said switch, a shunt path around said contacts and a relay controlled over a metallic circuit including said line for determining whether the said shunt will be effective or not.

11. In a telephone system, a line extending to a central exchange, serially related automatic switches at the exchange, a repeater interposed between the line and said switches, a switch control circuit extending from said repeater to one of said switches, means actuated following the seizure of said repeater to disable said control circuits, and means in said repeater operable over a full metallic circuit extending over said line for causing said switch control circuit to be made effective.

12. In a telephone system, a line extending to a central exchange, serially related automatic switches of the exchange, a repeater interposed between said line and switches, a control circuit extending from said repeater to one of said switches and including interrupter contacts for controlling the same to operate said switch, a shunt path around said contacts, and means controlled over a metallic circuit including said line for removing said shunt.

13. In a telephone system, a line extend-

- ing to a central exchange, a circuit including the two sides of said line and a relay in series with a source of current, a switch control circuit including impulse contacts on said relay, and means at the exchange controllable over a full metallic circuit including said line for maintaining said switch control circuit ineffective.
14. In a telephone system, a line extending to a central exchange, an automatic switch at the exchange, a repeater interposed between said line and switch, a control circuit extending from said repeater to said switch and including interrupter contacts for controlling the same to operate said switch, a shunt path about said interrupter contacts, a relay for controlling said shunt path, and means controlled over a metallic circuit including said line for causing the operation of said last relay.
15. In a telephone system, a line extending to a central exchange, an automatic switch at the exchange, a repeater interposed between said line and switch, a control circuit extending from said repeater to said switch and including interrupter contacts for controlling the same to operate said switch, a shunt path about said interrupter contacts, a relay for controlling said shunt path, and means controlled over a metallic circuit including said line for preventing the operation of said last relay.
16. In a telephone system, a line extending to a central exchange, an automatic switch at the exchange, a repeater interposed between said line and switch, a control circuit extending from said repeater to said switch and including interrupter contacts for controlling the same to operate said switch, a shunt path about said interrupter contacts, a relay for controlling said shunt path and means controlled over a metallic circuit including said line for causing the operation of said last relay in case the resistance of said metallic circuit is varied.
17. In a telephone system, a line extend-
- ing to a central exchange, an automatic switch at the exchange, a repeater interposed between said line and switch, a control circuit extending from said repeater to said switch and including interrupter contacts for controlling the same to operate said switch, a shunt path about said interrupter contacts, a relay for controlling said shunt path and means controlled over a metallic circuit including said line for causing the operation of said last relay in case the resistance of said metallic circuit is increased.
18. In a telephone system, a subscribers' line extending to a central exchange, a station on said line, automatic selector switches of two classes, means for operating switches of one class, and means controlled exclusively over a metallic circuit including said line for preventing the operation of switches of the other class.
19. In a telephone system, a line extending to a central exchange, serially related automatic switches at the exchange, a repeater interposed between said line and switches, a control circuit extending from said repeater to one of said switches and including interrupter contacts for controlling the same to operate said switch, a shunt path around said contacts, and a relay in said repeater energized solely over a metallic circuit including said line to render said shunt circuit effective to shunt said contacts.
20. In a telephone system, a line extending to a central exchange, an automatic switch at the exchange, a repeater interposed between said line and switch, a switch control circuit extending from said repeater and including a pair of impulse contacts, a shunt path about said impulse contacts including two pairs of normally closed contacts connected in series, and marginal means in said repeater for opening either contact pair.
- In witness whereof, I hereunto subscribe my name this 29th day of May, A. D., 1922.

JOHN WICKS.
